UNITED STATES PATENT OFFICE.

WILLIAM A. BOCHAU, OF BALTIMORE, MARYLAND.

PARACHUTE-KITE.

1,086,888.

Specification of Letters Patent. Patented Feb. 10, 1914.

Application filed March 3, 1913. Serial No. 751,684.

To all whom it may concern:

Be it known that I, WILLIAM A. BOCHAU, a citizen of the United States, residing at Baltimore, in the State of Maryland, have 5 invented certain new and useful Improvements in Parachute-Kites, of which the following is a specification.

This invention relates to a parachute kite or aerial toy.

10 The object of the invention is to provide a novel combination that shall include an inclined cord or wire, such as the string of a kite, up which a parachute or other toy device may travel, novel means to travel when 15 ascending the cord or wire and support the toy device in its ascent, and a releasing device revolute on the cord or wire in proximity to its high end to detach the traveler from the cord or wire and allow the parachute or other toy to go free in the air.

20 The invention is illustrated in the accompanying drawing in which,

Figure 1 is a view of a cord stretched in an inclined position and having the revolute releaser, and showing a parachute pendant from the cord as it is while ascending. Fig. 2 is a view on a larger scale of the cord, the revolute releaser, and the traveling hanger. Fig. 3 is another view of the same 25 parts seen in Fig. 2. Fig. 4 is a detached view of the traveling hanger. Fig. 5 is a cross-section on a larger scale of the revolute releaser, on the line 5—5 of Fig. 3.

30 The numeral, 6, designates a cord or wire stretched in an inclined position as it would be when the high end is attached to a kite and serving as the guide for an elevated kite, 7. Of course a cord or wire would have this inclined position were the high 35 end of the cord or wire attached to a high building or a tower.

35 A hanger, 8, having at its lower end an eye or loop, 9, to support whatever may be attached, such as slips of printed advertising matter, a written message, toy balloons, a 40 parachute, or other device, also has near its upper end a notch-shaped bend, 10, that takes over the stretched cord, 6, and the notch bend permits the loop-end, 9, to hang 45 pendant below the cord while it travels upward on the cord. The upper part of this hanger is suitably bent to form a pin, 11, that projects forward in a direction corresponding to the up-grade of the stretched 50 cord or wire.

55 The cord or wire, 6, is provided near its

high end with a revolute device having an axis in continuous alinement with the said cord or wire the axis remaining stationary and serving as a shaft around which the 60 device will revolve by the action of the wind. This revolute device serves to release or detach the hanger or traveler, 8, from the cord or wire, 6, and whatever happens to be supported by the said hanger is 65 allowed to drop or go free in the air.

The revolute releasing device comprises a metal shaft, 12, being a straight piece of wire having an eye, 13, formed at each of its ends; the stretched cord, 6, is cut a short 70 distance from its high end, or from the kite, if a kite is being used (say about twenty feet from a kite) and the cut ends of the cord are tied to the two eyes, 13, of the wire shaft, 12. Thus the wire shaft is in 75 perfect alinement with the cord, and constitutes a metal section of a fibrous cord. In practice a cord will sometimes twist up and then untwist which is objectionable because the released device revolves and to prevent 80 twisting or turning of the metal wire shaft, 12, one end thereof is provided with an arm, 14, secured to one of the eyes, 13, and said arm hangs downward below the stretched cord and serves as a pendant weight which 85 prevents the wire shaft, 12, from turning. The form or shape of the pendant weight arm, 14, may vary; in the present instance it is V-shaped, one end of the two prongs being hooked into the eye, 13, of the wire- 90 shaft, 12, that is next to the up-grade part of the cord, and the end of the other prong hooked over the cord, 6,—that part of the cord that is up-grade or nearest to the kite. The revolute part of the releaser consists 95 of two spiraled or twisted wings or blades, 15, similar to a propeller, that are joined to a central sleeve, 16, that fits loosely on the wire-shaft, 12; the two wings and the sleeve turn on the shaft. That end of the sleeve 100 that is next to the downwardly-inclined part of the stretched cord, 6, is forked or has two tangs, 17, which are spaced apart sufficiently to turn freely around the eye, 13. This forked or tang end, 17, of the revolute releaser knocks sidewise against the pin, 11, that projects forward from the approaching traveling hanger, 8, and the effect of this sidewise knock is to detach the notch-shaped bend, 10, from the cord, 6, and there- 105 upon the hanger and parachute, 18, or whatever the hanger may have been supporting, 110

will be free in the air, either to float away or drop to the earth.

Where the device is used with a kite, the revoluble releaser must be attached to the 5 cord, 6, at the time the kite is raised in the wind; then hanger, 8, should be placed on the stretched cord by the operator and the 10 parachute, 18, or any other desired article, suspended by a cord, 19, from the loop-end, 9, of the hanger. The wind moving toward 15 the kite will cause the pendant hanger and the parachute to slide or travel upward along the stretched cord until the pin, 11, of hanger is knocked by tangs, 17, of the revoluble releaser.

Having thus described my invention what I claim and desire to secure by Letters Patent is:

1. The combination of an inclined 20 stretched cord; a metal wire shaft in alignment with said cord and constituting a metal section of the cord; a weight arm, 14, hanging pendant from said metal section; a releaser device having spiraled 25 blades and revoluble on the metal section; and a traveler having at its upper part a notch-shaped bend to take over the stretched cord, and below the cord said traveler hav-

ing means to support articles—in operation said traveler to slide up the cord and be 30 detached therefrom by the said releaser device.

2. The combination of an inclined stretched cord; a metal wire shaft in alignment with said cord and constituting a metal 35 section of the cord; means attached to said wire shaft to prevent it from turning; and a releaser device revoluble on said wire shaft by the action of the wind.

3. The combination of an inclined 40 stretched cord; a hanger having a notch-shaped bend to take over said stretched cord and the upper part of said hanger having a pin that projects in a direction up-grade 45 on said cord, and below the cord said hanger having a pendant end for supporting articles; and the high end of the stretched cord provided with means to knock sidewise 50 against the said pin on the hanger and release the hanger from the cord.

In testimony whereof I affix my signature in presence of two witnesses.

WILLIAM A. BOCHAU.
